United States Patent Office.

ELIAS P. HALL, OF CHICAGO, ILLINOIS. #

Letters Patent No. 103,043, dated May 17, 1870.

IMPROVEMENT IN PADLOCKS.

The Schedule referred to in these Letters Patent and making part of the same.

To whom it may concern:

Be it known that I, ELIAS P. HALL, of Chicago, in the county of Cook and State of Illinois, have invented a new and useful Improvement in Padlocks; and I do declare that the following is a true and accurate description thereof, reference being had to the accompanying drawings and to the letters of reference marked thereon and being a part of this specification, in which—

Figure 1 is a plan of my lock, with the covering-plate removed.

Figure 2 is a vertical cross-section of the same on the line $x-x$ in fig. 1.

Figure 3 is a bottom plan of the key, also showing the tumblers in section.

Figure 4 is a sectional plan, showing the position of the dogs when the lock is opened.

Figure 5 is a section through the tumbler-wheels.

Like letters indicate like parts in each figure.

The nature of this invention relates to an improvement in the construction of padlocks, and

It consists—

First, in the construction and employment of a peculiarly-formed pair of tumbler-wheels, which mesh with each other, partly through cogs and partly through sheets projecting from the periphery of one into corresponding recesses in the other, alternately, the rotation of said wheels being effected by pushing between them a flat key, provided with proper openings, through which the studs in the wheels pass into their sockets.

Secondly, in the construction and arrangement of its several operative parts.

In the drawings—

A represents the case of my padlock, to which is pivoted the hasp B, in the usual manner.

In the periphery of the case, below the hinge of the hasp, is a transverse slot, a, through which the key C enters the lock.

b b are posts in the back plate of the lock, on which are journaled the tumbler-wheels D. The peripheries of these wheels are far enough apart to permit the key to pass between them.

On the periphery of each wheel are disposed at such intervals, and in such form as may be desired, gear-studs e, letters, or even medallions, if desired, those on each wheel projecting into sockets on the opposite wheel, when both are rotated simultaneously.

This rotation of the wheels is effected by pressing the end of the key against a stud, c, projecting from a flattened surface on each wheel, in the commencement, and is continued by the meshing of the wheels together by the studs and sockets described, the studs passing through openings d, properly disposed in the key, as shown in fig. 3.

Sectional cogs may be employed, in lieu of the studs or pins described, if preferred.

Across the face of one of the wheels directly, as shown, or diagonally, if preferred, a cog or gear-tooth, f, is formed, which gears with a corresponding re-

cess, f', in the face of the other wheel, the latter being, of course, enough larger to accommodate the thickness of the key, which is corrugated at the proper place, g, as shown in fig. 3.

A spiral spring, e, is secured to each of the posts b, and coiled about it, with one engaging with the interior of the wheel sleeved over it, so that the wheels are rotated outward, ready for the reception of the key.

Ordinary gears may be constructed on a projection from the periphery of one or both of the tumbler-wheels, or attached to them, thus compelling a simultaneous motion of both wheels, and, if necessary, dispensing with one of the coiled springs.

h is a post, on which are pivoted two or more tumblers, E, hooked at their upper ends, to engage with the opening in the point of the hasp, being thrown forward for that purpose by the springs i secured to their bases.

F is a dog, pivoted to the back of the case at j, and has a transverse bar or head, F', which is pressed down by the point of the hasp, when the latter enters the lock, as shown in fig. 1, but is thrown up by the spring k when the tumblers are withdrawn from the hasp, which movement of the dog ejects the hasp from the lock, as shown in fig. 4, and, until again pushed downward by the hasp entering the lock, the dog keeps the tumblers back until the hasp is down, thus permitting the use of longer tumblers than could be used if they had to be forced back by the hasp.

The tumblers are each provided with a notch, m, in the edge next the tumbler-wheels, which receive the pressure of the end of the key.

It will be noticed that the key must be constructed in its details to exactly accommodate the studs and cogs or the projections of the wheels, before it can commence rotating them, and that its end must press equally on each tumbler, to withdraw it from the hasp.

The tumblers are not set on the same plane, but one back of the other, requiring a key to project at that point on its end which is opposite the tumbler farthest removed from it.

When the key is withdrawn after unlocking, the hasp is again locked by pressing it down into the lock, its end forcing the dog down.

What I claim as my invention, and desire to secure by Letters Patent, is—

1. In the construction of locks, the tumbler-wheels D, provided with studs, cogs, and recesses, or their equivalents, and the key C, provided with corresponding openings and corrugations g, substantially as and for the purpose set forth.

2. The arrangement of the tumbler-wheels D, the tumblers E, the dog F, the springs i and k, and the hasp B, when constructed as described and for the purpose set forth.
